UNITED STATES PATENT OFFICE

WILLIAM J. BURTON, JR., OF WILMAR, CALIFORNIA

DESIGN FOR A VEHICULAR TOY

Application filed December 17, 1928. Serial No. 29,300. Term of patent 3½ years

To whom it may concern:

Be it known that I, WILLIAM J. BURTON, Jr., a citizen of the United States and resident of Wilmar, California, have invented a new, original, and ornamental Design for a Vehicular Toy, of which the following is a specification, reference being had to the accompanying drawing, forming a part hereof.

I claim:

The ornamental design for a vehicular toy substantially as shown.

WILLIAM J. BURTON, JR.
